UNITED STATES PATENT OFFICE.

JOHN DENNIS AND GEORGE B. CORAM, OF LOWELL, MASSACHUSETTS, ASSIGNEES, BY DIRECT AND MESNE ASSIGNMENTS, TO JOSEPH A. CORAM AND NATHAN CROSBY, OF SAME PLACE.

PRESS FOR PRESSING AND STAMPING.

SPECIFICATION forming part of Letters Patent No. 294,311, dated February 26, 1884.

Application filed June 8, 1883. (No model.)

To all whom it may concern:

Be it known that we, JOHN DENNIS, a citizen of the United States, and GEORGE B. CORAM, a subject of Victoria, Queen of the United Kingdom of Great Britain and Ireland, both residing in Lowell, in the county of Middlesex and Commonwealth of Massachusetts, have invented a certain new and useful Improvement in Presses for Pressing and Stamping, of which the following is a specification.

The press described herein is especially useful for pressing and stamping soap and materials of similar consistency, but is also adapted, if made of the proper strength, for making bricks, and the means described for adjusting the lower die and for raising the same after the impression is made are applicable to presses for embossing paper and similar materials.

Our invention relates, principally, to means for removing the work from the dies after stamping or pressing, to means for adjusting the lower die, and to means for adapting the upper surface of the table to receive die-boxes of different sizes.

In the accompanying drawings, Figure 1 is an isometric view of a press containing our improvements; Fig. 2, a vertical central longitudinal section of the same; Figs. 3, 4, 5, rear elevations of the cams, which respectively operate the upper die, the nippers, and the lower die; Fig. 6, an oblique view of the die-box; Fig. 7, a horizontal section of the press just above the table and nippers; Figs. 8 and 9, plans of the nippers and a cake of stamped material, in Fig. 8 the cake being released from the nippers, and in Fig. 9 the cake being held and carried forward by the nippers; Fig. 10, a rear elevation of the rock-shaft, arm, and links which operate the lower die, and said die, also a cross-section of the table; Fig. 11, a plan of the under side of the table; Fig. 12, a vertical longitudinal section of the lower die, means for adjusting the height of the same, and links; Fig. 13, a plan of the nippers provided with adjustable jaws, parts of the nippers and jaws being in section; Fig. 14, an oblique view of one of said adjustable jaws; Fig. 15, an oblique view of one of the dead-points and means for adjustably securing the same to the frame, a part of which frame is shown; Fig. 16, a plan of the parts shown in Fig. 15.

A denotes the frame of the press; B, the main

shaft; C, the driving-pulley; D, the gear on the main shaft, which gear takes into the gear D' on the shaft B', all of the above-denoted parts being of the construction and operation shown in Letters Patent of the United States No. 237,537, granted February 8, 1881, on the application of Charles L. Ingalls.

Secured to the shaft B' are three cams, E E' E'', Figs. 3, 4, and 5, so set that the points e in said cams will always be in the same direction from the axis of the shaft B'. The cam E operates the upper die, I, said die I being secured by its stem H' to the cross-head F, and adjusted in height, and the cross-head being guided in a vertical path by the guide-rods H, as shown in said patent. To the cross-head is rigidly secured the rod G, the upper end of said rod being provided with a slot, d, through which the shaft B' passes and guides said rod G vertically. A stud, h, which may be provided with a whirl, i, enters the groove of the cam E from the rod G, and the revolution of the cam E causes said rod G to have a reciprocating motion.

The lower die, I', is raised by the cam E'', rod G'', and connecting parts. The rod G'' has a slot, d'', stud h'', and whirl i'', which correspond in form and use to the slot d, stud h, and whirl i, respectively, in and on the rod G. The rod G'' is jointed at g', to allow its lower end to accommodate itself to the motion of the arm P', secured to the rock-shaft P, and is adjusted in length by a screw adjustment (at g'') in the usual manner, according to the point of its attachment to said arm P'. The arm P' is slotted endwise, and the lower end of the rod G'' is attached thereto by a screw-pin, which projects through said rod G'', through a washer, and through said slot, and is held in place by a nut, the pin having a shoulder, which presses the washer away from the rod and against the arm P'. The rock-shaft P has another arm, P'', secured to it. The arm P'' is pivoted to the upper end of a link, P'', and this link is pivoted at its lower end to the lower end of another link, P'', the upper end of the latter link being pivoted to the stem J of the lower die, I', so that the revolution of the shaft B' causes the lower die to rise and fall. The height of the lower die may be adjusted by making the stem J in two parts, j j', Fig. 12, and rigidly inserting a stud, j'', in the

lower part, j' , the upper end of said stud being provided with a screw, which enters a threaded hole in the upper part, j , of said stem J , so that after removing the die-box K from the 5 table the lower die may be turned around, and so raised or lowered. The die I is prevented from turning by the die-box or mold K (which it fits) when said box is in place. The mold or die-box requires to be changed for cakes of 10 different lengths and widths—the thickness of the cakes being regulated by the adjustment of the upper and lower dies—hence the bed-piece L of the table is made with an opening large enough to receive the largest die-box intended to be used with the press, and these 15 boxes are each provided with ears K' of sufficient length to allow of their being held against the bed-piece in the usual manner by screws or bolts K^2 , passing up into said bed-piece 20 through holes in said ears. On top of the bed-piece are placed four pieces, $L' L^2 L^3 L^4$, thick enough to rise to the top of the die-box when the latter is in place, the bed-piece L being provided with slots, through which cap-screws reach up into said four pieces. By 25 loosening the cap-screws the four top pieces $L' L^2 L^3 L^4$ may be moved toward or away from the center of the table, to fit the top of the die-box. The screws, being tightened, 30 hold the top pieces in place. The front piece, L^3 , is inclined downward, on its upper surface, from the top of the die-box to the front edge of the table, and the side pieces, $L' L^2$, are beveled off on their front inner corners, to 35 aid in the delivery of the stamped cakes or bars from the press.

Guides L^5 are used to direct the unstamped material to the die-box. These guides are secured by screws L^6 to the top of the piece L , 40 as shown. After the material is stamped by the pressure of the dies I I' in the die-box or mold K , both dies rise by the revolution of the cams E E' , the upper die starting a little in advance of the other, and the upper surface 45 of the lower die, I' , rising about one-quarter of an inch above the top of the die-box. The parts or points e of the three cams E E' E^2 are then directly over the axis of the shaft B' , and the dies are separated by a distance a little greater 50 than the thickness of the stamped bar or cake X , said bar adhering to one of the dies—generally the lower die. The dies now stop, (owing to the shape of the cams, because the shaft B' has a continuous rotary motion,) and the 55 nippers are quickly brought forward, as described below, and grasp the cake X , whereupon the nippers rest and the dies separate still farther, the lower die falling to its lowest position and the upper die rising to its highest 60 position.

The rod G' is provided with a slot, d' , stud h' , and whirl i' , corresponding to similar parts in and on the rods G G^2 . There is a vibrating lever, Q , the pivoted end of which is divided, 65 as shown, and pivoted at Q' to brackets Q^2 , secured to the bottom of the frame A . From the lever Q a slotted arm, Q^3 , projects backward,

to which the lower end of the rod G' is adjustably attached, just as the rod G^2 is attached to the slotted arm P' and for a similar purpose—that is, to vary the length of the stroke of the lever Q . The rod G' is also provided with a joint, g , (to allow its lower end to move back and forth with the arm Q^3 ,) and with a screw adjustment at g^2 to take up the slack. 70 The upper end of the lever Q is provided with three arms, Q^4 Q^5 Q^6 . To the rear end of the arms Q^5 Q^6 (which project back, as shown) are pivoted the rear ends of the nippers R R' at R^4 R^5 , and a rod, T , secured at its middle 80 point to the central forward-projecting arm Q^4 , projects through said nippers. Spiral springs S S , placed around the rod T , between the nippers and the arm Q^4 , crowd said nippers outward against the nuts T' T^2 , screwed 85 onto the ends of said rod T . The nippers are provided with the projections R' R^2 , which strike the dead-points R^2 R^2 as the nippers are vibrated by the lifting of the rod G' . The corners of the projections R' R^2 and of the 90 dead-points are chamfered or beveled off, so that, the beveled parts striking each other, (by the forward movement of the nippers,) the nippers are forced toward each other, and grasp and hold the stamped cake X , and then 95 rest, (as the central parts of said projections R' R^2 and dead-points just lap onto each other,) while the dies separate from the cake, as above described. As soon as the dies have so separated from the cake, the nippers again move 100 forward, still holding the cake, until the central parts of the projections and dead-points pass each other, when the nippers are opened by the outward pressure of the springs, thereby 105 releasing the cake, which drops on the incline L^3 and slides off the front of the table into any suitable receptacle.

In order that the nippers may not deface the cake X , the faces of the jaws of the nippers are covered with rubber or other suitable elastic pads, R^3 R^3 , secured by screws R^5 R^5 to said jaws, and in order that the jaws may be adjusted to cakes of different lengths, the jaws are made in separate pieces R^6 R^6 . (See Figs. 13 and 14.)

In Figs. 14 and 15 the jaws are angle-irons, provided with dovetails, which enter corresponding grooves in the front inwardly-projecting parts, R' R^2 , of the nippers. Stud-nuts S' S' are inserted in the transverse parts 110 of the jaws, and project through slots in the transverse parts R' R^2 of the nippers, and screws V V , passing through the nippers, engage with the nuts S' S' , and cause the jaws to slide on the nippers transversely, these screws 115 V V having many-sided heads, which can be turned by a wrench. The screws V V are prevented from endwise motion by pins or screws W W , which, being inserted in the tops of the nippers, enter annular grooves cut in said screws V V . The jaws are held in place by turning up nuts Y Y on the studs or shanks of the stud-nuts S' S' . The dead-points are dovetailed into angle-irons, Figs. 15 and 16, in or- 120 125 130

der that they may be readily removed when worn out, and in order to compensate for the wear on said dead-points the angle-irons are slotted in one direction, and the brackets are slotted at right angles to the slots in said irons, the brackets being secured to the frame A of the press, as shown. This allows the dead-points to be moved nearer together as they wear, and also allows them to be moved back-
ward or forward, to make the nippers close more or less quickly. It will be seen that the lower die has a positive motion in each direction. The lower die has heretofore been lifted by a hook which let go of the die at the proper time, allowing the die to fall of its own weight. This arrangement worked well when the press was run at a slow rate of speed; but when the machine was run too fast the lower die would sometimes jump out of the die-box and catch on the top of the same, and be broken by the descent of the upper die. The methods heretofore used of knocking off the stamped bars by a sudden blow, as shown in the patent above referred to, were open to the objection of mar-
ring one side of the bar, and of scraping off the characters impressed upon the upper and lower faces of said bar by the dies, which are in soap-presses commonly engraved with ornamental or advertising figures or devices.

30 We claim as our invention—

1. A press provided with a positive automatic picking-off device, as and for the purpose specified.
2. The combination of the die-box K, the lower die, I, and means for giving to said die a positive motion in both directions, as and for the purpose specified.
3. The combination of the dies, means for raising the same, means for causing the same to rest, means for causing the same to draw away from each other and the nippers, and

means for causing the same to advance and close, as and for the purpose specified.

4. The combination of the dies, means for raising the same, means for causing the same to rest, means for causing the same to draw away from each other, the nippers, and means for causing the same to advance and close, and means for causing said nippers to rest until the dies have separated from the stamped bar, as and for the purpose specified.

5. The combination of the lever Q, means for reciprocating the same, the nippers R R, hinged to said lever, and provided with the projections R' R', and the dead-points R² R², as and for the purpose specified.

6. The combination of the lever Q, means for reciprocating the same, the nippers R R, hinged to said lever, and provided with the projections R' R', the dead-points R² R², and means for opening said nippers, as and for the purpose specified.

7. The combination of the lever Q, provided with the arm Q³, the cam E', means for rotating the same, and the rod G', provided with the stud h', and adjustably connected to said arm Q³, as and for the purpose specified.

8. The combination of the die-box K, the table provided with an opening to receive said die-box, and means for adjusting the upper surface of said table to fit said die-box, as and for the purpose specified.

9. The combination of the die-box K, the bed-piece L, and the top pieces, L' L² L³ L⁴, and means for adjustably securing said top pieces to said bed-piece, as and for the purpose specified.

JOHN DENNIS.
GEORGE B. CORAM.
